UNITED STATES PATENT OFFICE.

LEWIS W. HUNTER, OF IRVINGTON, NEW JERSEY.

CARD-RETAINER FOR CARD-CASES.

1,255,751.

Specification of Letters Patent. Patented Feb. 5, 1918.

Application filed March 27, 1917. Serial No. 157,862.

To all whom it may concern:

Be it known that I, LEWIS W. HUNTER, a citizen of the United States, and a resident of Irvington, in the county of Essex and State of New Jersey, have invented a new and Improved Card-Retainer for Card-Cases, of which the following is a full, clear, and exact description.

The invention relates to card retainers for card cases, such as shown and described in the Letters Patent of the United States, No. 685,333, granted to Harry J. Hunter, on October 29, 1901.

The object of the present invention is to provide a new and improved card retainer for card cases, arranged to permit convenient adjusting of the retaining members to accommodate visiting or business cards of different width.

In order to accomplish the desired result, use is made of a card retainer having a base plate fastened to the back cover of a card case, the base plate having at one end a transversely extending guideway, and retaining flanges adapted to hold the cards between them and provided with angular arms slidably engaging the said guideway to permit of adjusting the said retaining flanges toward or from each other according to the width of the cards to be held in place, and fastening means for securing said arms in the adjusted position.

Figure 1 is a perspective view of a card case provided with the improved card retainer and with the card case in open position;

Fig. 2 is a sectional plan view of the same;

Fig. 3 is an enlarged sectional side elevation of the same with the card case in closed position; and

Fig. 4 is a perspective view of the clamping flange of the card retainer.

The card case illustrated in the drawings consists preferably of a front cover 10, a back cover 11 and a flexible connection 12 connecting the covers with each other, the said parts being preferably made of leather or other suitable material. The card retainer is applied to the back cover 11 and is provided for this purpose with a base plate 15 inserted between the body of the back cover 11 and the facing 16 thereof, as plainly illustrated in Fig. 3, and from one end of the base plate 15 extends integrally and at a right angle a guideway 17 disposed adjacent the flexible connection 12 and extend-

ing transversely of the covers 10 and 11. In the guideway 17 are slidably mounted arms 18 and 19 extending at right angles and integrally from the side flanges 20 and 21 between which the cards 22 are retained. The arms 18 and 19 are arranged one alongside the other and the arm 19 is provided with a stud 23 which extends through registering slots 24 and 25 formed transversely in the arm 18 and the guideway 17, respectively, as plainly indicated in Figs. 2 and 3. On the outer end of the stud 23 screws a clamping nut 26 against the outer face of the guideway 17 so as to securely fasten the arms 18 and 19 in the guideway after the said arms are adjusted in a transverse direction to move the retaining flanges 20 and 21 toward or from each other according to the width of the cards 22 to be accommodated in the card retainer. By reference to Figs. 1 and 2 it will be noticed that the guideway 17 is considerably less in length than the width of the covers 10 and 11 to permit of adjusting the retaining flanges 20 and 21 to a considerable extent and without the said flanges moving beyond the sides of the back cover 11 thereby accommodating cards 22 of a width corresponding to the length of the guideway 17, or cards approximately the width of the covers 10 and 11, or cards of any width intermediate the said two extremes.

The lower edges of the retaining flanges 20 and 21 are provided with inwardly extending seats 30 and 31 for the lowermost card 22 to rest on. The flange 20 is the seating flange and is provided at its free end with an inwardly projecting catch 32 normally engaging the adjacent edge of the card or cards held between the flanges 20 and 21. The free end of the other flange 21, which is the pressure flange, is provided with a curved portion 33 the end of which is adapted to bear against the adjacent edges of the cards 22 to hold the latter against accidental displacement. When it is desired to remove the uppermost card it is necessary first to swing the edge engaged by the curved portion 33 in an upward direction to allow of pulling the card free from the catch 32. This construction of the flanges 20 and 21 is practically the same as described in the patent above referred to and hence forms no part of the present invention.

It is understood that the user of the card

case on partly unscrewing the nut 26 can readily adjust the flanges 20 and 21 toward or from each other to correspond to the width of the pile of cards to be accommodated in the card case, and when the desired adjustment has been made and the cards have been placed in position then the operator screws up the nut 26 so as to securely fasten the arms 18 and 19 in the adjusted position to the guideway 17.

From the foregoing it will be seen that by the arrangement described cards as narrow as the length of the guideway 17 may be accommodated as well as larger cards up to 15 a width corresponding approximately to the width of the covers 10 and 11.

Having thus described my invention, I claim as new and desire to secure by Letters Patent:—

20 1. In combination, a card case having a front cover, a back cover and a flexible connection connecting the covers with each other, a base plate attached to the said back cover and having a rising guideway extending 25 transversely adjacent the said flexible connection, side flanges having angular arms slidingly engaging the said guideway to allow of adjusting the said side flanges toward or from each other according to the 30 width of the cards to be retained between

the said flanges, and means fastening the said arms in the adjusted position in the guideway.

2. A card retainer for card cases, comprising a base plate adapted to be attached to the card case, a guideway rising integrally from one end of the said base plate and extending across the card case, and card retaining side flanges provided with angular arms slidingly engaging the said guideway, 40 the latter and one of the said arms having registering slots and the other arm having a stud extending through the said slots, and a clamping nut screwing on the said stud to fasten the arms in the adjusted position in 45 the guideway.

3. A card retainer for card cases, comprising a base plate adapted to be attached to the card case, a guideway rising integrally from one end of the said base plate 50 and extending across the card case, card retaining side flanges provided with angular arms slidingly engaging the said guideway, the said side flanges being of angle iron shape in cross section, the bottom members 55 being adapted to support the sides of the cards, and means adjustably securing the said arms in the said guideway.

LEWIS W. HUNTER.
